MAX DRUCKERMAN, OF BROOKLYN, NEW YORK.

CIRCULAR SEAM FOR SEWED ARTICLES.

1,091,428.

Specification of Letters Patent. Patented Mar. 24, 1914.

Application filed March 7, 1913. Serial No. 752,575.

To all whom it may concern:

Be it known that I, MAX DRUCKERMAN, a citizen of the United States, and a resident of Brooklyn, in the county of Kings and State of New York, have invented certain new and useful Improvements in Circular Seams for Sewed Articles, of which the following is a specification, taken in connection with the accompanying drawing, which

10 forms a part of the same.

My invention relates to embroidery which is usually done by machine upon any suitable fabric, though it is to be distinctly understood that my invention covers embroidery upon any material through which the needles carrying the needle threads can pass.

The circular seam or embroidery covered by my present application may be used alone, or one or a plurality of them may be used in connection with other forms of embroidery to represent, for example, flowers upon a stem or stalk such for example as illustrated in Fig. 1.

25 In the accompanying drawings, showing illustrative embodiments of my invention, and in which the same reference numerals refer to similar parts in the several figures, Figure 1 is a plan view of a piece of material, as for example, fabric, embellished with three different forms of my embroidery representing flowers upon a twig; Fig. 2 is a plan view of the obverse of one of the flowers in Fig. 1, on an enlarged scale, showing my embroidery formed with two separate and independent needle threads, and one shuttle or locking thread; Fig. 3 is a plan view of the reverse of the embroidery shown in Fig. 2, many of the stitches being omitted

30 for purposes of illustration; Fig. 4 is a sectional view of a piece of fabric and a diagrammatic view of two needles and two needle threads employed in making the embroidery shown in Fig. 2 and Fig. 3; Fig. 5 is a vertical sectional view substantially on the line 5—5 of Fig. 1; Fig. 6 is a plan view of the obverse of the fabric showing a little different form of embroidery in which the needle threads do not overlap, the figure being on an enlarged scale; Fig. 7 is a plan view of a further modification in which three needle threads are employed, the diameter of the embroidered seam being substantially the same as that shown in Fig. 6 in which two needles are employed; and Fig. 8

is a plan view of a further modified form of my embroidery in which three different needles are used, but the diameter of the circular embroidery seam is enlarged.

In the illustrative embodiments of my invention, shown in the drawings, 1 is a piece of material through which the needles 2 and 3, Fig. 4, can pass. Usually this material is some woven fabric, though, of course, it is to be understood that my invention is not to be limited to such material. This material 1 is provided with an opening 4 and on the obverse has a plurality of what, for convenience, will be termed independent primary needle threads 5, 5 which are threaded through the fabric 1 by the needle 2 operating in a zig zag manner. These primary needle threads 5, 5 on the reverse form the primary needle loops 6, 6 extending from near the circumference of the circular seam toward its axis, and are locked or caught by the shuttle or locking thread 7. They also form the primary loops 10, 10 on the reverse extending out radially from the center, which loops also coöperate with the same locking or shuttle thread 7. On the obverse also is a plurality of secondary needle threads 8, 8, threaded through the fabric 1 by the secondary needle 3 in the ordinary zig zag manner, both needles 2 and 3 being preferably mounted on the same head. These secondary needle threads 8, 8 on the reverse form the secondary inwardly extending needle loops 9, 9 which are also caught or locked by the same shuttle or locking thread 7. They also form the radially extending secondary needle loops 11, 11 which are also connected by the same locking or shuttle thread 7, the one shuttle thread serving to lock all the loops formed by the needle threads. I also preferably, though not necessarily, place a binding cord 12 around the edge of the opening 4, which cord is secured in place by the different needle threads 5 and 8. It will be noted that in this form, shown in Figs. 2, 3, 4 and at 13 in Fig. 1, the embroidery is formed with independent needle threads which overlap each other. This gives a thick raised effect to the medallion or embroidery on that portion of the circular seam in which the plurality of needle threads are laid down. The relative length of the thickened portion of the medallion can, of course, be varied as found convenient or expedient. For purposes of

illustration I have in Fig. 5 shown the raised portion formed by the double thickness of needle threads extending from the opening 4 out to the point 14. From that 5 point to the circumference 15 of the embroidery only the secondary needle threads 8 would appear and consequently the portion 16, Fig. 5 of the embroidery would be thinner than the other portion. This gives 10 a very handsome effect to the embroidery as it permits the embroidery seam to taper off in thickness from the center to its circumference. It is, of course, to be understood that if the usual number of threads were shown, 15 both the obverse and reverse of my circular seam would have to be illustrated as a substantially solid black ring. In this form of my invention the take up mechanism of the machine serves to tighten the primary needle 20 threads 5 around the edge 17 of the opening 4 whether or not the binding cord 12 is used.

In some cases I may form my circular seam as shown in Fig. 6 and at 18 in Fig. 1. In this form the fabric 1 on its obverse is 25 provided with a primary needle thread 19 which extends part way to the circumference of the embroidery and on the reverse forms the primary needle loops 20, 20 which coöperate with the shuttle thread 21, this 30 primary needle thread serving to bind the edge 22 of the opening 23, it, of course, being understood that in the completed article the number of threads are greatly increased over those shown in this figure 35 which has to be more or less diagrammatic. A cord 12 may be employed as in Fig. 2 and Fig. 3 if desired. The secondary needle thread 24 is also upon the obverse of the fabric 1 and extends out to the periphery 40 25 of the complete circular seam forming on the reverse the secondary needle loops 26, 26 which are also caught by the same shuttle or locking thread 21. In this form of my invention the primary and secondary 45 needle threads 19 and 24 do not overlap.

In Fig. 7 and at 27 in Fig. 1, I have shown the fabric 1 having an embroidered circular seam of substantially the same diameter as that shown in Fig. 6 but instead 50 of using two needle threads I employ three needle threads; 28, 28 being the primary needle threads threaded by the primary needle (not shown); 29, 29 being the secondary needle threads threaded by the secondary needle (not shown) and 30, 30 being the third set of needle threads, all the needle threads being locked or caught by the single shuttle thread 31. In this form I have shown the different needle threads 55 overlapping. In some cases I may use three needle threads 32, 33, 34, Fig. 8, all co-operating with a single shuttle thread 35. In this instance the threads are the same as those shown in Fig. 7 except that the diameter of the circular seam has been enlarged 60 65

and the throw of the needles increased from that shown in Fig. 7.

By my invention I am enabled to get the most beautiful shading effects entirely regardless of whether or not the needle threads overlap each other. I imitate embroidery flowers or similar articles, by shading my circular seam from the center out toward the circumference of the embroidery, or I reverse this shading by shading the embroidery from the circumference in toward the center depending upon the particular flower or article being imitated. This is done for example by having a primary needle thread 5 of one color and having a secondary needle thread 8 of a different color. This is also true of the other primary and secondary needle threads 19 and 24, Fig. 6, and also of the triple needle threads 28, 29 and 30, Fig. 7, and 32, 33 and 34, Fig. 8. Where more than two needle threads are employed, the shading can be more delicate, as, of course, with three or more needle threads the shading will be more delicately and perfectly done 90 in that the colors merge from one needle thread into the next and from that into the third and so on. Where the needle threads overlap this shading is particularly pleasing. While I have shown only two or three 95 needle threads, it is, of course, to be understood that my invention is not to be limited to this number.

Having thus described this invention in connection with illustrative embodiments thereof to the details of which I do not desire to be limited, what is claimed as new and what it is desired to secure by Letters Patent is set forth in the appended claims.

1. A circular embroidery seam as an article of manufacture consisting of a piece of material having an opening and a plurality of independent radial and horizontal needle threads all extending out radially and lying on the face or obverse of the material, at least one set of independent needle threads extending into and binding the edge of the opening needle thread loops on the back or reverse of the material and a single shuttle or locking thread locking the loops 110 of the different independent radial needle threads.

2. A circular embroidery seam as an article of manufacture consisting of a piece of material having an opening and a plurality of independent radial and horizontal needle threads all extending out radially from the opening and all lying on the face or obverse of the material, said needle threads overlapping each other on the face 125 of the fabric, at least one of the independent needle threads being threaded into the opening in the material and serving to bind its raw edge needle thread loops on the back or reverse of the material, and a single 130

shuttle thread locking the loops of the different overlapping independent radial needle threads.

3. A circular embroidery seam as an article of manufacture consisting of a piece of material having an opening, a cord surrounding the opening, and a plurality of independent radial and horizontal needle threads which overlap each other on the face of the fabric, at least one of the independent needle threads being threaded into the opening in the material and serving to bind its raw edge and the cord needle thread loops on the back or reverse of the material, and a single shuttle thread locking the loops of the different overlapping independent radial needle threads.

4. An embroidered medallion as an ar-

ticile of manufacture comprising a piece of embroidery having an opening and three radial needle threads of different colors, at least one of the needle threads binding the raw edge of the opening, and at least one of the other needle threads being laid down on top of said needle thread to give a raised effect to the medallion, the different colors of the needle thread permitting various coloring and shading of the embroidered medallion needle thread loops on the back or reverse of the material, and a single shuttle thread to lock the loops of the different colored needle threads.

MAX DRUCKERMAN.
